CONTAINER HANDLING DEVICE

Bernhard F. Düscher, Santa Cruz, Calif.

Application May 21, 1937, Serial No. 144,019

4 Claims. (Cl. 294—87)

In the handling of various types of containers, such as milk bottles, for instance, in process of delivery, it is common practice to gather a number of bottles in the arms when several are to be delivered at one place, and to handle the empty bottles in the same manner. This method of handling the containers is highly objectionable, both from a sanitary point of view and the difficulty of handling the same without dropping or breaking any of them.

It is, therefore, the principal object of the present invention to provide means whereby the containers may be picked up and set down, either singly or several at a time, without the necessity of touching them with the hands.

It is another object of the invention to provide means of the character indicated so constructed and arranged that the container cannot be accidentally released therefrom.

Finally it is an object to provide means of the character indicated that will be economical to manufacture, simple in form and construction, and that will be strong, durable, and highly efficient in its practical application.

In the drawing:

Figure 1 is a perspective illustration of a device embodying my invention.

Figure 2 is a sectional view on line 2—2 of Figure 1, parts being broken away.

Figure 3 is a sectional view on line 3—3 of Figure 2, parts being broken away.

In the particular embodiment of the invention herein disclosed the device is capable of handling four containers at one time through the medium of the four units indicated by the reference characters A, B, C, and D. These four units are identical in construction and mode of operation, however, therefore but one unit will be described in detail, it being understood that the said unit may be duplicated as desired to secure a device of any desired capacity.

Referring, therefore, more particularly to the drawing the reference character 1 indicates a rectangular frame provided with spaced cross-bars 2 such as 2—2 supporting uprights 3 carrying the handle 4. Here the handle uprights 3 are disposed in the longitudinal median line of the frame 1 and are equally spaced from the ends of the frame so that it may be easily held in balance.

Referring now specifically to the unit A, a pair of leaves 5 are pivotally mounted on opposing sides of frame 1 as at 6, these leaves being disposed to overlie the space encompassed by the frame between the end of the frame and the adjacent upright 3.

The inner edges of the two leaves 5 approach each other along the median line of the device and swing upwardly as indicated by arrows 7, the said leaves being normally held in their lowered horizontal positions by means of springs 8 as at 9. These opposing edges of the leaves have semi-circular segments removed therefrom as at 10 to form a circular opening 11. In the present instance the opening 11 has a diameter slightly greater than the outside diameter of a milk bottle neck but less than the outside diameter of the bead encircling the top of the bottle neck.

By means of the construction described the device may be lowered over a bottle so that the neck of the bottle will be thrust upwardly through the opening 11, the leaves swinging upwardly to permit the passage of the top of the bottle. When the top of the bottle has cleared the edges of the opening 11 the spring action will cause the leaves to drop back into place, as shown in solid lines. The device now being raised, the bead on the upper edge of the bottle will seat on the top surfaces of the opposing leaves 5 and may be lifted with no danger of dropping the bottle.

To release the bottle the following mechanism is provided. On the upright 3 are mounted a pair of sheet metal members 12 to form a guide 13. In the guide 13 is slidably mounted a bar 14 having an outwardly directed finger piece 15 on its upper end. The lower end of the bar is offset as at 16 to seat upon the underlying cross-bar 2, and has a member 17 mounted thereon in parallel relation to the cross-bar. The member 17 is provided with an arcuate upper edge 18, and the several parts are so arranged that normally the leaves 5 rest upon the upper edge of the frame 1, but when the bar 14 is drawn upwardly the member 17 engages them and swings them upwardly.

By means of this last described mechanism the carrier of the device has merely to engage the part 14 with a finger and pull upwardly on the same when the bottle being carried is placed in position and it is desired to release the same. By lowering the device a little and operating the bar 14 as indicated the leaves 5 are swung upwardly sufficiently far to permit the device to be drawn upwardly over the bead on the bottle neck.

To prevent accidental release of the bottle by twisting the device sidewise thereon, I mount a bar 19 on the sliding bar 14 a little above the normal plane of the leaves 5 as shown. This bar operates as a stop to prevent the leaves opening far enough to permit the top of a bottle to pass between them, when in a normal position, but when the sliding bar 14 is pulled upwardly the

bar 18 moves with it and permits the leaves to open to the desired extent as clearly shown in dotted lines in Figure 2.

It will be clear from the foregoing description that I have provided a device whereby the operator may quickly pick up several bottles, in the present instance four, convey them to their destinations and quickly and easily release them, either one or more at a time.

10 It is to be understood, of course, that while I have herein shown and described but one specific embodiment of the invention, changes in form, construction, material, size, and mode of operation may be made within the scope of the appended claims.

I claim:

1. A bottle carrier comprising, a rectangular frame provided with spaced cross-bars having upstanding members mounted thereon and han-
20 dle connecting said members, bottle-neck engag-
ing leaf members pivotally mounted on opposing sides of the frame, resilient means disposed to urge the leaves into engagement with said frame and cross-bars, and an operating bar having a laterally directed finger-piece on its upper end
25 slidably mounted on each side of each upstand-
ing member, each operating bar being provided with means to engage two opposed leaves to raise the same when the bar is moved upwardly.

30 2. A bottle carrier comprising, a frame pro-
vided with an upstanding centrally disposed mem-
ber provided with a handle, bottle-neck engaging
leaf members disposed in pairs on each side of
35 the upstanding member and pivotally mounted on opposing sides of the frame, resilient means

disposed to urge the leaves into engagement with the frame, operating bars having laterally di-
rected finger-pieces on their upper ends slidably
mounted on opposite sides of the upstanding
member, each operating bar being provided with
means disposed to engage the adjacent leaves
and raise the same when moved upwardly. 5

3. A bottle carrier comprising, a frame pro-
vided with an upstanding centrally disposed
member provided with a handle, bottle-neck en-
gaging leaves pivotally mounted in pairs on op-
posing sides of the frame and on opposite sides
of the upstanding member, resilient means dis-
posed to urge the leaves into engagement with
the frame, operating bars having laterally di-
rected finger-pieces on their upper ends slidably
mounted on opposite sides of the upstanding
member, each operating bar having a member
mounted on its lower end to underlie the adjacent
leaves and provided with an arcuate upper edge
15 20 adapted to engage the leaves and spread the same
when moved upwardly.

4. The combination with a bottle carrier in-
cluding a frame having opposed leaf members
pivotally mounted thereon to normally rest on
25 the frame and having their opposing edges formed
to engage a bottle neck, an upstanding handle
on the frame, an operating bar having a laterally
directed finger-piece mounted for vertical sliding
movement on the handle and provided with
30 means to raise the leaves when moved upwardly;
of a cross-bar mounted on the operating bar to
overlie both leaves to limit the swinging move-
ment of the leaves relative to each other.
